No. 763,915.

PATENTED JUNE 28, 1904.

A. S. LIDDLE.

ATTACHMENT FOR RULES.

APPLICATION FILED APR. 20, 1904.

NO MODEL.

UNITED STATES PATENT OFFICE.

ALFRED S. LIDDLE, OF CHANUTE, KANSAS.

ATTACHMENT FOR RULES.

SPECIFICATION forming part of Letters Patent No. 763,915, dated June 28, 1904.

Application filed April 20, 1904. Serial No. 204,092. (No model.)

To all whom it may concern:

Be it known that I, ALFRED S. LIDDLE, a citizen of the United States, residing at Chanute, in the county of Neosho and State of Kansas, have invented certain new and useful Improvements in Attachments for Rules, of which the following is a specification.

This invention relates to improvements in braces for rigidly holding the members of an ordinary folding carpenter's rule at right angles to each other to form a square.

The object of the invention is to provide a neat, cheap, and effective holding device or brace for the purpose specified, and to this end I construct the brace of a single piece of spring metal and form at opposite ends a pivot and an engaging point, respectively.

Many other objects and advantages will be hereinafter referred to and be particularly pointed out in the claim.

In the drawings, Figure 1 is a perspective view of my invention in use. Fig. 2 is a similar view, the rule being closed. Fig. 3 is an enlarged section on the line 3 3, Fig. 1, the brace being above its seat prior to the locking action between the parts. Fig. 4 is an enlarged detail sectional view showing the engaging point locked. Fig. 5 is a cross-sectional view on line 5 5, Fig. 4, but showing a staple to form a seat for the catch. Fig. 6 is a detail perspective view of the preferred form of locking-bar.

The same numerals refer to like parts in all the figures.

1 and 2 represent two members of an ordinary folding carpenter's rule, and 3 the hinge which connects the same. Two openings 4 and 5 are formed in the member 1, in which are fitted eyelets 6. These eyelets are for the purpose of preventing wear between the parts, as will readily be understood.

7 indicates a brace formed of a single piece of spring metal, having its ends 8 and 9 bent at right angles to the body 10 thereof. The end 9 is passed through the eyelet 6 and is shouldered at 6^a and then headed at 11 to form a pivot. The opposite bent end 8 of the brace is provided with a slight projection 8^a, adapted to engage a depression 8^b, formed in one of the eyelets, or it may engage the under side of a staple 8^c, driven in the face of

the rule across one side of one of the eyelet openings. To prevent the brace projecting beyond the face of the rule, I may cut out the latter, as at 16 and 17, although this is not absolutely essential.

When it is desired to convert the rule into a square, the brace is turned on its pivot 9 to the position shown in Fig. 1 and its end 8 is forced into the eyelet 13. The brace being formed of spring metal it can readily be raised, as shown in Fig. 3, to bring the end 8 into engagement with the eye 13, then applying a little pressure the bent end 8 is forced down and the projection 8^a catches in its coacting seat and automatically locks the brace. In disengaging the brace it is withdrawn from the eyelet 13 and turned to the position shown in Fig. 2, and the end 8 enters the eyelet 5, the latter being of the same construction as its corresponding eyelet 13.

From the foregoing description it is evident to one skilled in the art to which the invention appertains that I have produced a practical, neat, and durable device for converting a rule into a square. The arrangement of parts is such that liability of wear and loss of details is greatly reduced. By constructing the brace of one piece of spring metal enables me to dispense with the cost of separate parts as well as the expense incident to assembling them.

What I claim as new is—

A rule composed of several members, a hinge connecting the members, an opening formed in each member, one of said openings having a seat therein, a brace constructed of spring metal having at its ends respectively a pivot and a catch, a projection on the catch, the pivot fitting in an opening of the rule member and being headed to hold it therein, the projection on the catch being forced into its seat which serves to lock the brace in position across the joint of the square, substantially as described.

In testimony whereof I have signed my name to this specification in presence of two witnesses.

ALFRED S. LIDDLE.
